UNITED STATES PATENT OFFICE.

FRANK E. CROY, OF WATAUGA, TENNESSEE.

SASH-LOCK.

1,252,405.

Specification of Letters Patent.

Patented Jan. 8, 1918.

Application filed February 2, 1917. Serial No. 146,141.

To all whom it may concern:

Be it known that I, FRANK E. CROY, a citizen of the United States, residing at Watauga, in the county of Carter and State of Tennessee, have invented certain new and useful Improvements in Sash-Locks; and I do hereby declare the following to be a full, clear, and exact description of the invention, such as will enable others skilled in the art 10 to which it appertains to make and use the same.

This invention relates to improvements in sash locks.

The object of this invention is the provision of a novel lock, which is adapted to be applied to window frames of the usual construction and so arranged as to be partially concealed from view and adapted to engage the upper and lower sash within the window 20 frame to hold the same against movement in one direction.

A further object of this invention is the provision of a sash lock of this character, which is provided with novel means whereby 25 a pair of pivoted pawls may be adjusted to fit various size window frames, so that one pawl may engage the upper sash and one pawl the lower sash and means for holding the pawls into engagement with the sashes, thus permitting the sashes to be moved in only one direction, until the pawls 30 are released.

A still further object of this invention is the provision of a sash lock which is provided with a novel means which is located 35 on the inner side of one side of a window frame, so that the dogs which engage the rack bars carried by the sashes may be released to permit the sashes to be moved in either direction.

A still further object of this invention is the provision of a sash lock which is adapted 40 to be secured to one side of a window frame on the inner side thereof and located in the weight chamber and is constructed of suitable material embodying a socket which is journaled to the outer sides of the sides of the window frame and a horizontal shaft having one end journaled in the socket and 45 its opposite end extending through the inner sides of the sides of the window frame, a latch arranged on said shaft, pawls journaled on said shaft and arranged to extend

in opposite directions and extending through the sides of the window frame adapted to 55 engage the upper and lower sashes, spring means for holding the pawls into engagement with the racks carried by the sashes, and means associated with the shafts and located in the path of the pawl, whereby 60 upon the turning of the latch, the pawls will be moved out of engagement with the racks to permit the sashes to be raised or lowered in either direction.

A still further object of this invention is 65 the provision of a window sash lock of this character, which will be simple, practical and comparatively inexpensive in construction and one that can be manufactured and sold at a small cost.

With these and other objects in view the invention consists in the novel combination and arrangement of parts hereinafter more fully described and set forth in the claims 70 hereto appended.

In the drawings:

Figure 1 is a fragmentary front elevation of my improved sash lock, applied to a window frame,

Fig. 2 is a vertical sectional view of one 80 side of the window frame illustrating my improved sash lock,

Fig. 3 is a sectional view taken on the line 3—3 of Fig. 2,

Fig. 4 is a horizontal sectional view taken 85 on the line 4—4 of Fig. 2,

Fig. 5 is a sectional view taken on the line 5—5 of Fig. 2,

Fig. 6 is a fragmentary sectional view 90 illustrating the operating latch which is attached to one end of the shaft.

Like numerals of reference designate corresponding parts in all the figures of the drawings.

Referring more particularly to the drawings, the numeral 1 designates a window frame of the usual construction having the sides 2 and ends 3. The sides 2 define the usual weight receiving compartments which are attached to the sashes, so that the same 100 may be easily raised and lowered. Secured in the window frame is the upper sash 4 and lower sash 5.

The sides 2 of the window frame are provided with the usual strips 6 on their outer 105 sides, which are arranged at a spaced dis-

tance apart and define grooves in which the sashes 4 and 5 are arranged to slide. The sashes 4 and 5 have one of their faces in abutting engagement with the outer sides 5 of the sides 2 and partially cut away as at 7 to provide longitudinally extending grooves in which are secured the longitudinally extending rack bars 8, which are secured thereto by screws 9 or any other 10 suitable fastening means. The rack bars 8 are provided on their outer faces with teeth 10 and the teeth on the upper sash are inclined downwardly while the teeth on the lower sash are inclined upwardly, the purpose 15 of which will be hereinafter more fully described. The side rails 2 are provided with slots 11, which slots are located near the center of the side rails 2 and extend horizontally through the side rails 2 and 20 communicate with the weight receiving compartments therein.

The slots 11 are offset with relation to one another and one slot is located in the groove in which the lower sash 5 slides and the 25 other slot is located in the groove in which the upper sash 4 slides. The slot which is located in the groove in which the upper sash slides is in superposed relation to the slot which is located in the groove in which 30 the lower sash slides. The inner wall of each of the slots is inclined as at 12, so as to permit the pawls to readily move into active position.

The sides 2 are provided with the outer 35 strips 13 and inner strips 14, which form the weight casing. A socket 14' is provided at one end with an attaching flange 15, which is secured to the inner side of one of the outer members 13 and the socket is arranged 40 in a horizontal plane and extends in the direction of the inner member 14. The inner member 14 is provided with an opening 16, which is in direct alinement with the bore 17 in the socket member 14'. The opening 45 16 terminates into a rectangular recess 18 which is located on the outer side of the inner member 14 so as to be located on the interior of a room in which the window frame is located.

50 The flanges 15 on one end of the socket 14' extend laterally in opposite directions and define attaching members, whereby the socket may be secured in a horizontal plane by screws 19 or other suitable fastening 55 members to the inner side of the outer member 13.

A bearing bracket 20 is provided with attaching flanges 21, which are provided with 60 openings 22 adapted to receive fastening elements 23 for securing the bearing bracket to the inner side of the side 2 and intermediate the members 13 and 14. The bracket 20 is provided with a horizontal opening 24, which opening is in alinement with the bore

17 of the socket 14' and the opening 16 in 65 the member 14.

A shaft 25 is extended through the opening 16 in the side member 14 and through the opening in the bracket 20 and has its inner end journaled or rotatably mounted in 70 the bore 17 of the socket 14', the outer end of the shaft projecting beyond the side member 14.

The shaft 25 is provided with a plurality of inwardly extending openings 26, which 75 openings are arranged at a spaced distance apart so as to permit a pin 27 to be removably arranged therein, the purpose of which will be hereinafter more fully described.

A pair of arcuate pawls 28 have one end 80 enlarged as at 29, and the enlarged ends are substantially circular and provided with openings 30 to receive the shaft 25. The opposite ends of the pawls 28 taper to a point 31 and are adapted to extend through 85 the slots 11 for engagement with the rack bars 10 carried by the upper and lower sashes for holding the upper and lower sashes against movement in one direction. The pawls 28 are keyed to the shaft 25 and 90 extend in opposite directions and are arranged on opposite sides of the bracket 20, as clearly shown in Fig. 2 of the drawings.

The pawl 28 which is arranged to engage the lower sash 5 has formed from its circular 95 inner end a vertical projection 31, which is adapted to extend upwardly beyond the horizontal shoulder 32, formed on the bearing bracket 20, the purpose of which will be hereinafter more fully described. The 100 lower pawl 28 is also provided on one side face with an inwardly extending recess 33, which is adapted to be engaged by the removable pin 27, which holds the lower pawl 28 in position on the shaft, so that upon rotation of the shaft, the pawl will be moved 105 out of engagement with the rack teeth 10 carried by the lower sash and permits this sash to be moved in either direction.

The pawls 28 are each provided on their 110 outer sides adjacent their tapering ends 31 with longitudinally extending grooves 34. The longitudinally extending grooves 34 arranged on the outer side of each of the pawls are located intermediate the opposite side 115 longitudinal edges of the pawls and are adapted to receive therein one end of the spring arms 35, which spring arms have their inner ends connected to the horizontal body portion 36. The horizontal body portion 36 and spring arms 35 are all formed of a single piece of wire and the arms are formed on the opposite ends of the horizontal body portion and extend in opposite directions and arranged to be seated in the 125 grooves 34, so as to normally urge the pawls outwardly through the slots 11 in the side 2 of the window frame.

The body portion 36 is secured to the bracket 20 centrally of its ends by a suitable staple 37 or any other suitable fastening member suitable for the purpose.

5 A bell crank lever 38 is pivotally secured upon the horizontal shoulder 32 of the bracket 20 as at 39 and has one arm arranged to engage the vertical portion 31 and the inner enlarged end of the lower pawl 28. The opposite arm of the bell crank lever 38 is provided adjacent its end with an opening 40 and is adapted to be pivotally secured to the upper pawl 28 by a link 41, which is connected to a staple 42 carried by the upper pawl 28 so that upon movement of the shaft in one direction, the lower pawl will be moved inwardly against the tension of the spring arm 35, thus moving its vertical portion into engagement with 10 the arm 43 of the bell crank lever, moving the same on its pivotal point 39, thus pulling the upper arm 28 out of engagement with the rack teeth 10 of the upper sash member simultaneously.

15 25 The outer end of the shaft 25 which extends through the opening 16 in the member 14, is bifurcated as at 44 to provide arms 45, the purpose of which will be hereinafter more fully described.

30 35 A metal keeper plate 46 is seated within the recess 18 of the outer side of the inner member 14 and is provided with a flange 47, which engages the outer side of the member 14 to limit the inward movement of the keeper 46 within the recess 18.

The keeper plate 46 is provided with an opening 48 through which the outer end of the shaft 25 extends.

40 45 The flange 47 of the keeper plate 46 is secured to the member 14 by suitable rivets, screws or the like designated 49 so as to hold the same in position within the recess 18 and prevent accidental displacement therefrom.

50 55 A latch 50 is provided with a shank 51 which is pivotally mounted between the arms 45, defined by the bifurcating of the outer end of the shaft 25. The shank 51 is pivotally secured therein by a pin 52, so as to permit the latch 50 to be swung upwardly and positioned within the keeper plate 46. The keeper plate 46 and latch 50 are provided with thumb slots 53, which permit the latch 50 to be moved outwardly in a horizontal plane for rotating the shaft for moving the pawls 28 out of engagement with the teeth 10 carried by the upper and lower sashes 4 and 5, which are located within the window frame 1.

60 65 The shaft 25 which is provided with a plurality of spaced openings 26 permits the pawls to be adjusted to compensate for various widths of the side 2 of the window frame, and the shaft and dogs or pawls are

protected by a plate 54', which is secured to 65 the inner sides of the members 13 and 14 and in spaced relation to the front side 2. The plate 54' may be constructed of any suitable material, such as tin, wood or the like and it prevents the weights from contacting with 70 or interfering with the operation of the sash locking device.

In operation, the latch 50 is grasped by the fingers of the operator and turned in the direction away from the operator, thus moving the pin 27 in engagement with the walls of the recess 33 moving the lower pawl 28 rearwardly against the arms 43 of the bell crank lever 38, pulling outwardly on the upper pawl 28 simultaneously moving the 80 pawls out of engagement with the rack teeth 10 carried by the upper and lower sashes 4 and 5.

The shank 51 carrying the pin 52 is adapted to be journaled in the openings in the end of the shaft 25, the openings in the end of the shaft 25 are provided with diametrically opposed slots which communicate at one end with the openings and the opposite ends extend out through the end of the shaft 90 to facilitate slipping out of the pin and latch from the shaft to permit the shaft to be removed from the casing when desired.

What is claimed is:

1. A sash lock comprising a rotating shaft, 95 bearings supporting the shaft, pawls adjustably mounted on said shaft and on opposite sides of the bearings, one of said pawls being keyed to the shaft, means pivotally secured to the bearings and coöperating 100 with each of the pawls whereby upon rotation of the shaft the keyed pawl will move the other pawl simultaneously therewith out of engagement with the sashes, and spring means for normally urging the pawls 105 into active position.

2. A sash lock comprising a rotating shaft, means pivotally secured to one end of the shaft for rotating the shaft, pawls adjustably mounted upon the shaft, said pawls extending in opposite directions and one of the pawls being keyed to the shaft, means engaging the inner ends of each of the pawls for moving the pawls in inactive position during the rotation of the shaft, and spring 110 means for normally urging the pawls into active sash engaging position.

3. A sash lock comprising a horizontal shaft, a bearing supporting the shaft centrally thereof, a pair of pawls adjustably mounted on the shaft and extending in opposite directions and located on opposite sides of the bearings, one of said pawls being keyed to the shaft, a bell crank lever pivoted at its medial portion to the bearings, the arms of the bell crank lever being in engagement with the inner ends of the pawls, said bell crank lever facilitating the 125

movement of the pawls in inactive position upon rotation of the shaft, and means rigidly secured to the bearings and engaging the pawls for normally urging them into sash engaging position, and a latch pivotally secured to one end of the shaft for facilitating the rotation of the same.

In testimony whereof I affix my signature in presence of two witnesses.

FRANK E. CROY.
